UNITED STATES PATENT OFFICE.

ALVAN M. HILL, OF NEW ORLEANS, LOUISIANA.

DESIGN FOR A SPOON.

SPECIFICATION forming part of Design No. 20,723, dated May 19, 1891.

Application filed April 16, 1891. Serial No. 389,223. Term of patent 7 years.

To all whom it may concern:

Be it known that I, ALVAN MEREDITH HILL, a citizen of the United States, residing at New Orleans, in the parish of Orleans and State 5 of Louisiana, have invented certain new and useful Improvements in a Design Patent for Spoons; and I do declare the following to be a full, clear, and exact description of the invention, such as will enable others skilled in

10 the art to which it appertains to make the same.

The figure is a front view showing spoon in a vertical position.

15 The leading feature of my design consists in a handle formed in shape of a monument with a pyramid-shaped base, which is attached to a bowl of spoon, with a pedestal in close proximity to end of handle, upon which rest a figure and two flags.

20 A is the handle of spoon, which is shaped like a shaft of a monument; B, the lower portion of handle. C is the bowl of spoon, in which are pressed the figure of pelican and

young resting upon a bale of cotton, with stalks of sugar-cane and rice projecting from 25 the respective sides of cotton-bale, with a crescent upholding same, with cotton-bolls on one side of crescent and an alligator lying in a horizontal position by side of crescent; D, the end of spoon-handle, showing 30 figure on pedestal, with two flags on each side of figure.

What I claim is—

The design for spoons herein shown and described, the same comprising the monumental-shaft-shaped handle, the pyramid-shaped attachment of handle to bowl of spoon, the figured bowl of spoon, and pedestal-shaped end of spoon, with figure and flags, as 35 set forth.

In testimony whereof I affix my signature in presence of two witnesses.

ALVAN M. HILL.
